UNITED STATES PATENT OFFICE.

ROBERT ANDERSON, OF CINCINNATI, OHIO, ASSIGNOR TO THE FERRO CONCRETE CONSTRUCTION COMPANY, OF CINCINNATI, OHIO, A CORPORATION OF OHIO.

TEMPORARY FRAMING FOR USE IN CONCRETE-WORK.

No. 835,724.

Specification of Letters Patent.

Patented Nov. 13, 1906.

Application filed August 19, 1905. Serial No. 274,816.

To all whom it may concern:

Be it known that I, ROBERT ANDERSON, a citizen of the United States of America, and a resident of Cincinnati, county of Hamilton, 5 State of Ohio, have invented certain new and useful Improvements in Temporary Framing for Use in Concrete-Work, of which the following is a specification.

My invention relates to the framing with 10 which the metallic members of buildings in the course of construction are surrounded in order to form molds for the plastic concrete covering the said members to hold the concrete in shape until it hardens.

15 The object of my invention is a framework which may be readily removed after the cement has set. This object is attained by the means illustrated in the accompanying drawings, pointed out in the specification, 20 and set forth in the claims.

Referring to the drawings, in which like parts are indicated by similar reference-letters wherever they occur throughout the various views, Figure 1 is a plan view of a portion 25 of flooring supplied with a framework embodying my invention, the horizontal sheeting being partially broken away to show the parts beneath it. Fig. 2 is a sectional view taken upon line $x x$ of Fig. 1. Fig. 3 is 30 a sectional view taken upon line $y y$ of Fig. 1, upon an enlarged scale. Fig. 4 is a detail view of the swinging supporting-arm and the I-beam. Fig. 5 is a detail perspective view of one of the braces for the joists. Fig. 6 is a 35 side elevation of a part of one of the sides of the frame. Fig. 7 is an elevation of a joist supplied with the swinging supporting-arms at its ends.

Referring to the parts, I-beams A, A', A², 40 and A³ are secured together and mounted upon columns A⁴ in the usual manner.

The vertical sides of the mold for holding the concrete about the web of the I-beams are formed by the sides B, B', B², and B³ of a 45 wooden rectangular frame, which members are secured to each other at their ends by nails or in any other suitable manner. This framework has secured to the ends B B² battens b, b', b², and b³, to which metallic swinging arms C are pivoted. These arms C are 50 turned outward at their ends c and terminate in a notch c', which engages the I-beams A A² to support the framework. Sides B' B³

have secured to them at intervals a series of battens b⁴. At the side of each batten b, b', 55 b², b³, and b⁴ the lower edges of the sides B, B', B², and B³ have notches b⁵, the lower ends of which notches are covered by a metallic strip b⁶, leaving a hole large enough to allow the members c of the supporting-arms 60 C to pass through them.

Within the frame composed of the members B B³ after it has been supported upon the I-beams a series of joists D are placed adjacent to each of the battens b⁴. Joists D 65 are of a length slightly less than the width of the frame B B³. To the ends of each joist D swinging supporting-arms C are pivoted upon a bolt C², which projects through the joist and upon the side opposite the arm C receives 70 a metallic brace E, which is slotted at e to pass over the bolt C². Braces E have at their ends sharpened burs e' to be forced into the battens b⁴, to brace the battens so as to hold the members B' B³ at a fixed distance 75 apart and at a fixed distance from the I-beams A' A³.

After the joists have been secured in place sheeting F is placed over the top of the joists, meeting the members B B' of the frame 80 to form the complete sides for the metal surrounding the I-beam. The opening beneath the I-beams is the last to be closed, being left open for the purpose of allowing shavings and dirt to be swept through to fall 85 to the ground. The lower ends of battens b⁴ below the I-beams are connected by cleats g, placed at intervals to support a board G, which is of a width equal to the distance between the side B³ of one frame 90 and the side B' of the adjacent frame. Concrete H is then filled in the mold formed by the board G, the sides B³ B', and the sheeting F, as shown in Fig. 3. After the concrete is set the framing is removed in the following manner: The ends of the bolts C² are loosened. The swinging arms C are rotated about the bolts to disengage the I-beams. 95 In order that the swinging arms may readily disengage the I-beams without disturbing the cement which has formed about them, the edges c³ and c⁴ are cut upward from an arc having its center at the bolt c² and the edge c⁵ is cut downward from an arc having its center at the bolt c², the radius of each of 100 said arcs being the shortest distance between

the said sides c^3 c^4 c^5 and the bolt c^2 , so that when the swinging arm C is swung about its pivot the sides c^3 , c^4 , and c^5 , which contact the cement, tend to draw away, so as not to 5 disturb it. The swinging arms having been disengaged from the I-beams, the braces E are pushed back out of engagement with the battens b^4 , and the frame is disengaged from the adjacent frame by uncoupling the cleats 10 g , when the whole framework may be lowered away from the concrete.

What I claim is—

1. A framework for use in concrete construction consisting of frames formed by connected side and end pieces of a form adapted to be placed in the spaces formed between the horizontal beams of the structure, arms secured to the frames and adapted to be swung outward to engage the beams, means 15 for locking the arms after the engagement, members for closing the spaces between the lower edges of adjacent frames, and a covering for the top of the frames.

2. A framework for use in concrete construction consisting of frames formed by connected side and end pieces to be hung in the spaces between the horizontal arms of the structure, joists within each frame, and swinging arms pivoted to the joists and adapted 25 to be swung beneath the frame at their lower ends to engage the beams.

3. A temporary framework for holding the plastic concrete in concrete construction con-

sisting of frames to be hung in the spaces between the horizontal beams, joists within the 35 frames, swinging arms pivoted to the joists and adapted to pass beneath the frames and to engage the beams, braces adapted to slide upon the joists and to engage the sides of the frames, and means for locking the braces of 40 their engaging frames.

4. In a temporary framework for use in concrete construction the combination of frames to be hung in the spaces between the horizontal beams of the structure, joists with 45 the frame having at each of their ends pivot-bolts, swinging arms pivoted upon the bolts and adapted to be swung inward at the lower ends to engage the beams, and slotted braces reciprocating upon the pivot-bolts and adapt- 50 ed to be moved inward to engage the frames.

5. In a temporary framework for concrete construction the combination of frames to be hung in the spaces between the horizontal beams of the structure, the lower edges of the 55 frames being notched at intervals, joists within the frame, swinging arms at the ends of the joists adapted to pass through the notches and engage the beams, means for locking the swinging arms after the engage- 60 ment, and strips closing the lower ends of the notches below the arms.

ROBERT ANDERSON.
